DEVICE FOR SEVERING ROLLED MATERIALS

Paul E. Fuchs, Colorado Springs, Colo.

Application July 28, 1947, Serial No. 764,054

2 Claims. (Cl. 206—59)

1

This invention relates to a device for severing a selected length of rolled material from the remaining material in the roll.

The use of rolled materials such as masking tape, the so-called "Scotch tape," surgical tape and similar materials usually involves the selection of a required length of the material and then the severance of such length from the remaining material in the roll. Such severance may be effected, of course, by means such as a knife or shears which are not connected with the rolled material or the spool, hub or axle upon which the material is mounted. Severance of the selected length of material by such means is frequently inconvenient, awkward and time consuming.

In addition, such means of severance frequently permits the severed end of the material remaining in the roll to adhere to the roll in such a manner that the selection of an additional length of the material is difficult. In an attempt to meet certain of the aforesaid difficulties, there have been developed heretofore devices to sever selected lengths of material which involve a cutting edge held in a position parallel to the axis of the roll of material by framework attached to the roll hub or spool. Such devices, however, because of their shape and bulk are not readily portable and, in addition, leave exposed an appreciable length of material, with consequent slow loss of adhering qualities of adhesive material, contamination, adherence of foreign matter, and other undesirable results.

The present invention has been designed to furnish a compact, easily portable cutter for rolled materials which, after severance of a selected length of the material, leaves exposed only a fragmentary length of the remaining material, which exposed portion, however, is sufficiently long to permit ready selection of an additional length of the rolled material. This invention consists of a cutter-type hub or spool, or, in the alternative, an annular cutting ring. The cutting edge is thus placed in a position which is concentric with and immediately adjacent to the roll of material.

To afford a better understanding of the present invention, reference will now be made to the accompanying drawings. In the drawings, in which like parts have been designated similarly:

Fig. 1 is a plan view of a device built according to the present inventive concept;

Fig. 2 is a vertical section along line 2—2 of Fig. 1; and

Fig. 3 is a fragmentary section of a modified

2

form of device embodying features of my invention.

In the forms of construction illustrated, the reference character 12 designates the rolled material which is wound upon a spool 13. The reference character 14 designates a hub plate, the center portion 15 of which is offset inwardly, thus forming a shoulder 16. The outside diameter of the shoulder 16 is only slightly less than the inside diameter of the spool 13 so that the hub may be pressed into the spool. The hub is prevented from readily rotating in or falling out of the spool by the frictional engagement of the shoulder 16 with the inner circumferential surface of the spool and is prevented from being pressed too far into the spool by the inwardly bent outer portion 17 of the hub, the outer rim of which outer portion 17 engages the adjacent side surface of the spool when the hub is pressed into the spool.

At the other end of the spool 13 is a cutter hub 18. As in the case of the hub 14, the center portion 19 of the cutter hub 18 is offset inwardly. The outside diameter of the shoulder 20 is the same as that of the shoulder 16 so that the cutter hub 18 may be pressed into the spool. The cutter hub 18 is prevented from readily rotating in or falling out of the spool by the frictional engagement of the shoulder 20 with the inner circumferential surface of the spool. When the cutter hub 18 is pressed into the spool, the inner face of the inwardly offset outer portion 21 of the cutter hub engages the adjacent sides of the rolled material 12 and the spool.

A cutting edge 23 is formed on the outer periphery of the cutter hub 18. In the preferred design illustrated in Fig. 2, the outer circumferential portion 22 of the cutter hub 18 is bent away from the plane of the portion 21 at preferably an angle of approximately 45° and is either serrated or sharpened to a knife edge to form the cutting edge 23.

Preferably, the cutting edge extends around the full periphery of the cutter hub 18, but it is apparent that, as a modification, illustrated in Fig. 1, the serrations or other cutting edge may be segmented around the periphery.

In another modification of the invention, shown in Fig. 3 the outer circumferential portion of the cutter hub 18 is not bent away from the plane of the portion 21, but extends on in the same plane, which is at right angles to the axis of the rolled material 12 and the spool 13. The periphery is again serrated or sharpened to a knife edge to form the cutting edge 23a.

In use, when a length of the rolled material

12 is selected by unrolling from the roll, such length is then rotated to the side on which the cutter hub 18 is located and in a plane which is approximately tangential to the roll at the point at which severance is desired, thus placing the selected length over the cutting edge 23. The selected length may be severed at any time after it has been moved over the cutting edge, but it will be apparent that if a square end on the selected length is desired, such length should be rotated as aforesaid to a position parallel with the axis of the roll 12 and the spool 13. The selected length is severed from the remainder of the rolled material by moving such selected length in the direction of the roll and spool axis, thereby shearing the material on the cutting edge 23.

Obviously, instead of the construction illustrated, the cutting edge 23 may be constructed as an integral part of the spool 13 or may be constructed in an annular ring which is held in a position adjacent to the rolled material 12 and the spool 13 by proper assembly with the spool or a hub.

In using the several forms of the invention hereinbefore described and/or illustrated, the operator grasps the loose end of the rolled material and draws a desired end from the roll by the usual manipulation. When the desired length is reached, the material is moved laterally into contacting relation with the cutting surface and severed. Due to the substantially right-angled turn required, a folded over end forms on the new end of the roll, thus providing a pick-up surface for the next use of the roll.

It should be understood further that two techniques may be employed in the lateral movement. In the first of these, the edge of the unrolled strip opposite the cutting surface is drawn across the roll underneath the loose end and first brought into contact with the cutting surface, followed by continued pressure across the width of the strip until it is completely severed. This action produces a substantial twist at the end of the roll providing a convenient pick-up surface.

The other operation requires that the far edge of the withdrawn strip shall be turned from the top downwardly to engage the cutting surface in substantially perpendicular relation. This produces a diagonal line of adhesion at the end of the roll with a single fold of triangular shape loosened from the roll to function as the next pick-up portion.

Where reference is made in this specification to rolled material, it is intended to designate a variety of such materials and particularly friction tapes such as cellulose tape, surgical tape, adhesive tape, masking tape and similar materials.

From the foregoing, it will be apparent that the structural forms herein illustrated and described are well suited to practice the present invention, and it will be understood that modifications may

be availed of within the spirit and scope of the hereunto appended claims. In this connection, it will be understood that the particular structural forms disclosed herein are merely illustrative of different methods of practicing the invention and so long as the cutting edge is placed circumferentially adjacent to the rolled material, the principle of the present invention will be satisfied.

10 What I claim and desire to secure by Letters Patent is:

1. The combination with a spool and a roll of material on the spool, of a hub member mounted in one end of said spool having a hub plate including a central spool-engaging portion and an offset peripheral flange engaging one side of the spool and terminating substantially at the juncture of the spool and roll of material, and a cutter hub member positioned in the opposite 15 end of said spool having a central spool-engaging portion and an offset peripheral flange of greater diameter than the first-named offset peripheral flange, said second offset peripheral flange extending to the juncture of the spool and roll of material and having an outer integral portion lying flatwise against the adjacent surface of the roll of material, said flange of greater diameter terminating in a circumferential portion beyond the outer surface 20 of the roll of material and having a cutting edge for severing material of the roll.

2. The combination with a spool and a roll of material on the spool, of a hub member mounted in one end of said spool having a hub plate including a central spool-engaging portion and an offset peripheral flange engaging one side of the spool and terminating substantially at the juncture of the spool and roll of material, and a cutter hub member positioned in the opposite 25 end of said spool having a central spool-engaging portion and an offset peripheral flange of greater diameter than the first-named offset peripheral flange, said second offset peripheral flange extending to the juncture of the spool and roll of material and having an outer integral portion lying flatwise against the adjacent surface of the roll of material, said flange of greater diameter terminating in a circumferential portion beyond the outer surface 30 of the roll of material and having a cutting edge for severing material of the roll.
